GRIPPER DEVICES

Thomas Blair Hawkes, 315 Trumbull Road,
Manhasset, N.Y.

Original application Apr. 1, 1953, Ser. No. 346,164.
Divided and this application Sept. 27, 1956, Ser. No.
612,536

3 Claims. (Cl. 153—48)

The present invention relates generally to stretch-forming machines, and more particularly to improved gripper devices for securely clamping the ends of a metal workpiece to be stretched. This application is a division of the copending parent application Serial No. 346,164, filed April 1, 1953, now abandoned.

In the stretch-forming technique, the ends of a metal blank or shape must be gripped so that the metal therebetween can be tensioned sufficiently to elongate the material beyond its elastic limit, thereby imparting a permanent set thereto. In one form of stretching machine, two sets of gripper devices adapted to clamp the ends of the metal sheet are disposed on either side of a central table for the forming die. The table is carried on hydraulic rams whose rise and fall are under the control of the operator. Provision is made to hold the sheet tangentially to the curvature of the die and to stretch the sheet to a degree approaching the yield point on the material whereby upon release of the gripper devices the work retains the shape of the die. There are other forms of such machines, and a stretcher leveler also requires the use of gripper.

Gripper devices are usually constituted by opposing jaws which serve to clamp the end of the metal blank. When the workpieces are of widely varying shape and size, conventional gripper devices are incapable of conforming to the contour of the workpiece, as a result of which the gripping action is uneven and certain portions of the workpiece are inadequately clamped.

Another difficulty experienced with conventional gripper devices arises from the fact that the pull of the workpiece, in the course of stretching, exerts a lateral force on the jaws, thereby tending to shift the upper jaw relative to the lower jaw. This displacement produces a mismatch of the jaws and hampers the gripping action. Furthermore, when the pressure exerted downwardly on the upper jaw is by means of a hydraulic piston operating within a cylinder, the lateral forces produced by the pull of the workpiece tend to displace the piston from its axial position within the cylinder. This displacement is injurious to the mechanism of the hydraulic apparatus and acts to score and otherwise mar the cylinder wall and the surface of the piston.

Wedge type grippers using a wedge angle adequate for good holding power, require long linear motion of the wedges. This makes a bulky, inconvenient, arrangement. The present invention provides a more compact form with the same or greater holding power.

In view of the foregoing, it is an object of this invention to provide an improved gripper device having jaws adapted efficiently to grasp bars or sheets of varying size and shape.

More particularly, it is an object of the invention to provide a gripper device constituted by an upper jaw which cooperates with a lower jaw and is adapted to assume a profile conforming to the upper surface of a metal blank having a non-uniform thickness. A significant feature of the invention resides in the fact that the gripper

2

per device operates effectively with sheets tapering in thickness from one side to the other, or whose edges are warped and buckled. Prior art wedge or toggle type grippers do not provide a large enough jaw opening in such cases.

Yet another object of the invention is to provide a gripper device having interengaging upper and lower jaws adapted to resist lateral stresses tending to displace the jaws. Another salient feature of the invention is that the jaw construction is such as to isolate the vertically-operating hydraulic system from lateral forces whereby the axial position of the piston is maintained under exceedingly heavy workpiece tension conditions.

For a better understanding of the invention as well as other objects and further features thereof, reference is made to the following detailed description to be read in connection with the accompanying drawings wherein like components in the several views are identified by like reference numerals.

20 In the drawings:

Fig. 1 is an elevational view of a stretch-forming machine including gripper devices in accordance with the invention;

Fig. 2 is a vertical section taken through one of the gripper devices of Fig. 1;

Fig. 3 is a front elevational view of the gripper device, partly broken away;

Fig. 4 is a section taken in the plane of lines 4—4 in Fig. 2;

30 Fig. 5 is a vertical view similar to that of Fig. 2 but in which a modified form of gripper device is shown;

Fig. 6 is an elevational view, partly broken away and partly in section of the gripper device of Fig. 5;

Fig. 7 is an enlarged detail view, shown in elevation, partly in section, of the lower hydraulic piston and its pivotal connection to the upper movable jaw of the modified form;

Fig. 8 is a detail view in elevation of the lower portion of the lower piston of the modified form; and

40 Fig. 9 is a side elevation of Fig. 8.

Referring now to the drawings and more particularly to Fig. 1, a stretch press including gripper devices in accordance with the invention comprises a die table 10 for supporting a die 11 of suitable shape. Table 10 may be raised or lowered in position by means including a hydraulic ram, reciprocal in a cylinder 12 and controlled by an operator from an instrument console.

The table 10 is located between two gripper devices, generally designated by numerals 13 and 14, and including hydraulic cylinders 15 and 16, the devices being designed to engage and hold opposite ends of a workpiece. Gripper devices 13 and 14 are mounted on carriages 17 and 18, and are tiltable thereon about respective pivot pins 19 and 20 by means of tilting motors 21 and 22. 55 Also provided for the carriages are lead screws 23 and 24 for adjusting the position of the gripper devices longitudinally with respect to the die table. Other arrangements may be used, such as hydraulic cylinders.

In operation, a workpiece is supported over the die 11 and held along its opposite side edges by gripper devices 13 and 14. This workpiece is pulled and set permanently in its desired shape by applying tension increasing to a point where at least portions of the material are under tensile stresses between its yield point and its ultimate breaking point. This operative condition is achieved by restraining or holding the opposite edges of the workpiece, or pulling on said edges in opposing directions through the powered movement of the gripper devices 13 and 14 while the die 11 is hydraulically forced upward against the under side of the workpiece.

The gripper devices 13 and 14 are identical in structure, Fig. 2 therefore illustrating only the structure of de-

vice 14. The gripper device comprises a jaw head 25 in the nature of a beam, the head being provided with an anvil 26 projecting from the front thereof. The head is pivotally supported on its carriage by pin 20 to permit it to swing vertically about the axis of the pin which is 5 parallel to the gripper jaws.

Seated on anvil 26 is a lower fixed jaw piece 27 in the form of a continuous bar extending substantially the full length of the anvil. The front face of jaw piece 27 is aligned with the front face of anvil 26 but the 10 width of the jaw piece is smaller than that of the anvil whereby a channel 28 is defined between the rear face of jaw piece 27 and the adjacent wall of jaw head 25. To secure the jaw piece against displacement with respect to anvil 26, the under surface of the jaw piece and the 15 upper surface of the anvil are provided with complementary serrations. The lower jaw 27 is affixed to anvil 26 by means such as screws 29.

Formed in jaw piece 27 is a recess extending the full length thereof for accommodating a series of wear plate 20 inserts 30 at equally spaced positions therealong. Cooperatively arranged with respect to the lower jaw piece 27 is a movable upper jaw piece 31 in the form of a continuous bar extending the full length of jaw head 25 and provided with a longitudinally extending recess 32 for accommodating a series of aligned wear plate inserts 33 at positions corresponding to that of inserts 31 in the lower jaw piece and cooperating therewith to grip the margin of a workpiece W-P to be stretched and shaped over the die. This workpiece may be in the form of a metal sheet or bar of uniform or varying shape and contour as heretofore explained. The upper inserts 33 are retained in the upper jaw piece by means such as screws 34.

The movable upper jaw piece 31 is provided with a lip 35 depending downwardly therefrom and dimensioned for insertion in the channel 28 behind the lower jaw piece, whereby the front face of the lip abuts the rear face of the lower jaw piece 27. Lip 35 serves as a guide and stop for aligning the edge of the workpiece 33 or any other workpiece to be gripped and stretched. The lip functions also to prevent relative stress and lateral movement in the direction of pull during the stretching operation as between the upper and lower jaws.

To effect downward movement of the upper jaw 31 so as to clamp the workpiece for stretch-forming, and subsequent upward movement to release the stretched workpiece, a row or bank of main hydraulic pistons 36 is provided, each of which is reciprocable in respective cylinders 37 bored in jaw head 25.

The upper jaw piece 31 is secured to the lower end or stem of the main pistons and against the rear face of a shoulder 38 depending therefrom by means of studs 39. These studs pass through oversize holes 40 in said shoulder and are threadedly received in the upper jaw piece. The upper jaw piece 31 is of deformable metal and is so designed whereby it is permitted to flex when subjected to hydraulic pressure by the piston, thereby causing the several gripping inserts 33 carried thereby to conform with the upper surface of the workpiece which is engaged. The number of inserts and the spacing therebetween are such as to permit the ready deformation of the upper jaw as described. For example, twelve equally distributed inserts may be employed along the jaw head as against seventeen cylinders.

To allow for bending of the flexible upper jaw piece, the holes 40 are somewhat larger in diameter than the studs 39, thus affording the necessary clearance for relative movement or play between the jaw piece and the pistons. It is important to note that the lip 35 which engages the rear face of the lower jaw 27 not only acts to prevent relative movement of the jaw piece but also functions to avoid lateral displacement of the pistons against the wall of the cylinder. Thus the lateral pull

of the workpiece during the stretching operation is impressed upon the depending lip, but is kept away from the cylinder, which effect materially improves the hydraulic action. This lip also acts as a locator when inserting sheet or bar stock.

To hold the workpiece W-P tangentially to the sides of the die as it is being stretched and shaped, there is connected to the jaw head 25 a nose-piece 41 extending substantially the full length thereof. Nose-piece 41 is attached to jaw head 25 by means such as threaded studs 42. Nose-piece 41 presents a convexly curved surface 43, under and against which the workpiece is placed, the nose-piece serving as a guide to the metal blank while it is brought to position. It may either be in the form of a single continuous bar, as shown, extending substantially the full length of the jaw head, or it may be of sectionalized construction consisting of a series of pieces which are arranged end to end in interconnection or articulated.

A row or bank of hydraulic point units are associated with the upper jaw 31 of the gripper device, each unit including, as already indicated, a main piston 36 reciprocable in a cylinder bore 31 formed in jaw head 25. In accordance with the invention these power units are designed to be hydraulically actuated in a manner whereby initially a relatively low pressure is applied and thereafter a much higher or intensified pressure is applied to develop the necessary gripping forces.

For this purpose, each of cylindrical bores 37 is enclosed at its upper end by a cylinder head 44 which in turn is surmounted by an intensifier cylinder 45 in axial alignment with the lower cylinder bore. Intensifier cylinder 45 is closed at its top by a second cylinder head 46. Cylinder head 44 and intensifier cylinder 45 are connected together and to jaw head 25 by studs 47.

Cylinder head 44 defines a hydraulic pressure chamber 48 enclosed by the top of main piston 36 and the side wall of the cylinder. Cylinder head 44 has a bore therethrough for the reciprocation therein of an intensifier piston rod 49, the lower end of which has a cylindrical flange 50 extending into a counterbore 51 in the piston 36 for reciprocating movement therein. The upper end of piston rod 49 is connected to an intensifier piston 52 reciprocable in intensifier cylinder 45. The upper end of counterbore 51 is partially enclosed by a cap 53 secured to main piston 36 to provide an abutment for the intensifier piston flange 50 by which said flange is able to lift the main piston and thereby lift the upper jaw 31 during certain phases of operation.

Flange 50 is smaller in diameter than counterbore 51 to define an annular passage 54 for the escape of working liquid therethrough. The hole in the cap 53 through which the intensifier rod 49 passes is slightly larger in diameter than said rod, thus providing annular clearance 55 around said rod for flow communication with the interior of counterbore 51 and hydraulic pressure chamber 37. Means including pipe 56 are provided to feed fluid into the intensifier chamber above the intensifier piston 51. Means including pipes 57 are provided to feed fluid below intensifier piston 52 in the intensifier chamber. Means including pipe 58 are provided to feed fluid above main piston 36 in the main hydraulic chamber.

As disclosed in greater detail in the copending application, the main and intensifier cylinders act in conjunction with a hydraulic fluid reservoir and valve system 65 whereby the main cylinder functions to move the upper jaw into engagement with the lower jaw to grip the workpiece. Means are provided which automatically are operable when the movement of the main piston is arrested upon engagement of the movable jaw with the workpiece for intensifying the hydraulic pressure acting on the main piston to enhance the gripping force of the jaws.

In the embodiment of the invention shown in Figs. 5 to 9, the hydraulic actuation system for the jaws may be substantially identical to that shown in Fig. 1, save for

the structure of the main piston. Hence this hydraulic system is omitted in Figs. 5 to 9 except for the main piston and its linkage to the upper jaw of the grippers. Basically the difference between the gripping devices in Figs. 1 and 5 is that in the latter the upper jaw structure is sectionalized.

Referring now to Figs. 5 to 9, each of the gripper devices is provided, as in the case of Fig. 1, with a jaw head 25 from which projects an anvil 26 on which is seated a lower fixed jaw piece 27 in the form of a continuous bar extending the full length of the anvil and coated thereto by means of serrations. Screws 29 serve to hold the lower jaw piece 27 in firmly locked relation with the anvil 26.

In place of the spaced inserts shown in the embodiment of Fig. 1, there is provided a continuous bar or wearplate 60 extending along the full length of the low jaw piece, the wearplate being secured to the jaw piece by screws 61. The wearplate has its gripping surface roughened or serrated as at 62 to afford a more positive grip on the blank W-P.

The upper jaw structure is constituted by an assemblage of movable upper jaw sections 63. The movable upper jaw sections receive the motive power from a row of hydraulic main pistons 64, each piston having an upper jaw section 63 depending therefrom. The upper jaw sections are pivotally mounted on the lower end of the pistons in a manner affording enough play or free swinging movement to effect alignment with respect to that part of the marginal surface which is to be gripped. Each of the upper jaw sections are hydraulically and separately actuated so as to give a uniform and direct gripping pressure between the upper and lower gripping jaws, even though the workpiece is tapered, bent or irregular along its marginal surface to be gripped. In other words, the sectionalized upper jaw is caused generally to assume the configuration of the marginal surface of the workpiece.

The main piston 64 is reciprocal in the hydraulic cylinders 37 formed in the jaw head 25. The upper jaw sections 63 which constituted the upper jaw assembly extend substantially along the full length of the jaw head 25.

The upper jaw sections 63 of each gripper device are pivotally secured to the lower ends of the pistons 64 by headed steel pins 65. The piston 64 is provided at its lower end with a centrally located arcuate projection or rib 66, the rib being dimensioned so as to fit freely into a similarly shaped recess formed in the upper jaw section to provide a seat 67. The seat 67 is flanked by a pair of ears 68 and 69, each ear being apertured to receive the shank of a stud pin 65 which also passes through an oversized hole 70 in the rib 66. The aperture in ear 69 is threaded to receive the threaded end of the pin 65. The arcuate rib 66 and the arcuate seat 67 are of the same radii and are adapted for sliding engagement, thereby coating with the loose-fitting hole to provide a loose pivotal connection.

In order to reduce friction during the gripping action between the rib 66 and its mating seat 67, the center portion of the rib is relieved centrally, leaving two spaced arcuate lands 71 and 72 to bear on the seat. From this arrangement it will be evident that the pressure transmitted to the upper jaw section and its serrated insert 73 will be through the arcuate seat. The function of stud pin 65 is for the purpose of retracting the upper jaw sections upon opening the grip of the jaws and to permit the loose pivotal movement of the upper jaw section. To permit this movement, operating clearances 74 are left between adjacent jaw sections.

The gripping inserts 73 are received in recesses in the lower surface of each of the upper jaws and are held therein by screws 75. Each upper jaw section has a depending lip portion 76 which is received in a channel behind the low jaw piece and operates to keep all of the

sections in alignment. The lip portions, as previously described, prevent lateral displacement of the jaws.

While there has been shown what is considered to be a preferred embodiment of the invention, it will be manifest that many changes and modifications may be made therein without departing from the essential spirit of the invention. It is intended, therefore, in the annexed claims to cover all such changes and modifications as fall within the true scope of the invention.

10 I claim:

1. In a power press for stretch forming metal blanks of widely varying shape and size, a gripper device for clamping one edge of said blank and comprising a pair of cooperating jaw structures for holding the blank therebetween, one of said structures being movable relative to the other and being constituted by a continuous rectilinear bar of resilient material adapted when clamped on the metal blank to flex so as to assume a profile conforming to the surface of the blank engaged thereby, said movable jaw structure being provided at its rear side with a depending lip portion adapted to set down in back of the other structure to resist displacement of said jaws when said blank is subjected to stretching forces; and apparatus for applying gripping pressure to said movable structure comprising a row of independent power units formed by hydraulic mechanisms and extending along said movable jaw structure, and means loosely coupling each unit to said movable jaw structure to permit said structure to assume the desired profile when pressure is applied thereto.
2. In a power press for stretch forming metal blanks of widely varying shape and size, a gripper device for clamping one edge of said blank and comprising a pair of cooperating jaw structures for holding the blank therebetween, one of said structures being movable relative to the other and constituted by a continuous rectilinear bar of resilient material adapted when clamped on the metal blank to flex so as to assume a profile conforming to the surface of the blank engaged thereby, said movable jaw structure being provided at its rear side with a depending lip portion adapted to set down in back of the other structure to resist displacement of said jaws when said blank is subjected to stretching forces, and apparatus for applying gripping pressure to said movable structure comprising a row of hydraulic cylinders extending along said movable structure, a piston reciprocal in each cylinder and having a shoulder projecting longitudinally from one end thereof, said bar being seated against the end of said pistons and laterally against the shoulders thereof, and means loosely coupling said bar to said shoulders to permit said bar to flex with respect to said shoulders and into conformity with the surface of the blank engaged thereby.
3. In a power press as set forth in claim 2 wherein said loose coupling means are constituted by studs connecting said shoulders to said bar, said studs passing through oversize bores in said shoulders, whereby said bores provide clearance permitting relative movement between the bar and the shoulders.
